UNITED STATES PATENT OFFICE.

CHARLES W. HERRIN, OF KANSAS CITY, MISSOURI.

ROTARY DRILLING APPARATUS.

Application filed July 6, 1925. Serial No. 41,660.

My invention relates to rotary drilling apparatus of the type disclosed by my co-pending application filed November 12, 1924, Serial No. 749,444, now Patent No. 1,562,549, issued November 24, 1925. The present invention differs from the one disclosed in said co-pending application in the mechanism for adjusting the bits to active and inactive positions and in cooperating elevator mechanism whereby the sleeve carrying said bits may be raised or lowered upon the drill stem.

In order that the invention may be fully understood, reference will now be had to the accompanying drawings, in which:

Fig. 1 is a vertical section of the apparatus showing the sleeve being lowered to active position upon the drill stem.

Fig. 2 is a side elevation, partly in section, of the apparatus ready to release the sleeve from the drill stem so that said sleeve may be elevated to the surface with the bits.

Fig. 3 is a view somewhat similar to Fig. 2 with the elevator mechanism in position for lifting the sleeve and the bits to the surface.

Fig. 4 shows the sleeve and the bits in drilling position; the elevator mechanism having been removed.

Fig. 5 is an enlarged vertical section of the upper portion of the apparatus with the elevator mechanism being lowered preparatory to lifting the sleeve with the bits from the well.

Fig. 6 shows the parts disclosed by Fig. 5 in the position which they assume after the sleeve has been lowered to operative position and the elevator mechanism is ready to be lifted from the well.

Fig. 7 shows a broken vertical section of the lower portion of the mechanism with the bits about to contact the inclined segmental guides whereby said bits are directed into active engagement with the chuck at the lower end of the drill stem.

Fig. 8 is a view similar to Fig. 7, excepting that the bits have been lowered into active engagement with the chuck.

Fig. 9 is a cross section, slightly reduced, on line 9—9 of Fig. 5.

Fig. 10 is a side elevation of a nut forming a part of the elevator mechanism.

Fig. 11 is a side elevation of an internal nut which is adjustable in the nut disclosed by Fig. 10.

Fig. 12 is a plan view of said internal nut.

Fig. 13 is a side elevation of a tubular dog-carrying member which coacts with the nuts disclosed by Figs. 10 to 12, inclusive. 60

Fig. 14 is a plan view of the parts disclosed by Fig. 13.

Fig. 15 is a detail side elevation of a plunger constituting a portion of the elevator mechanism. 65

Fig. 16 is a detail side elevation of a tubular element which in practice is mounted in the upper end of the sleeve and adapted to be engaged by the elevator mechanism when the sleeve is to be raised or lowered upon 70 the drill stem.

Fig. 17 is a detail vertical section of the sleeve.

Fig. 18 is an enlarged cross section on line 18—18 of Fig. 1. 75

Fig. 19 is a cross section on line 19—19 of Fig. 7.

Fig. 20 is a cross section on line 20—20 of Fig. 8.

Fig. 21 is a reduced irregular cross section on line 21—21 of Fig. 7 with the sleeve removed. 80

Fig. 22 is a broken detail perspective of the lower portion of the drill stem and a chuck fixed thereon. 85

Referring now more particularly to the sleeve and the parts intimately associated therewith, 2 designates the rotary drill stem which is made up of sections united by couplings 4, the sections being added from 90 time to time as the well is bored out.

6 designates the sleeve which is removably mounted on the stem 2 with which it is caused to rotate when in operative position by diametrically opposed feathers 8, which 95 fit in corresponding longitudinal grooves 10 arranged internally within the sleeve 6 and provided at their lower ends with flaring mouths 12 whereby said grooves are caused to register with the feathers 8 when 100 the sleeve 6 is being lowered to active position.

The sleeve 6 is provided adjacent to its lower end with a pair of bits 14 which are provided at their upper ends with pivots 16 105 mounted in the sleeve 6. The pivots 16 are threaded at their upper ends and provided with nuts 18 which loosely rest upon the lower walls of the recesses 20 formed in the sleeve 6 to receive said nuts. The recesses 110

20 have lateral extensions 22 to enable a pin to be inserted in the holes 24 of the nuts for the purpose of screwing them upon the pivots 16 or removing them therefrom when 5 the bits 14 are to be removed and sharpened. The bits 14 are of flat rectangular formation with cutting edges 15 at their lower ends.

The sleeve 6 is provided at its lower portion 10 with diametrically opposed recesses 26 to permit the bits 14 to describe approximately a quarter of a revolution when turning from inactive position disclosed by Fig. 7, to the active position disclosed by Fig. 8, 15 and vice versa. The bits 14 are prevented from turning far enough on their pivots 16 to get out of proper relation with the associate mechanism by stops 28 which project upwardly from said bits 14 into grooves 30 20 communicating with the lower end of the bore of the sleeve 6.

32 designates a chuck fixed to the lower end of the drill stem 2 for the purpose of locking the bits 14 in active position, shown 25 by Figs. 2, 3, 4 and 8. Said chuck 32 is provided with diametrically opposed slots 34 into which the bits 14 are directed as they are lowered from the position disclosed by Fig. 7 to that disclosed by Fig. 8, by a pair 30 of segmental inclined guides 36 formed at the upper portion of said chuck 32. The upper portion of the chuck 32 is reduced in diameter to freely enter the lower end of the sleeve 6 and is divided into two segmental 35 parts 35 by the slots 34. Each segmental part 35 tapers downwardly at one end as indicated at 37 to clear the lower ends of the bits 14 as they move downwardly upon the inclined guides 36 formed in the opposite 40 ends of said segmental parts 35. On entering the slots 34 in which they snugly fit the bits 14 are held from spreading apart by integral ribs 38 which fit within corresponding grooves 40 formed in the chuck 32 and 45 communicating with slots 34, Figs. 19 and 20. In order that the bits 14 may turn with their pivots 16 from the position shown by Figs. 7, 19 and 21 to the position best disclosed by Figs. 8 and 20, the lower portion 50 of the drill stem 2 is provided with oppositely disposed longitudinal recesses 42 and 44, Figs. 1, 7, 8, 19, 20 and 22.

The upper ends of the recesses 42 and 44 are beveled as indicated at 46 and 48, respectively, so that when the sleeve 6 is raised to release the bits 14 from the chuck 32 the inner upper corners of said bits 14 55 will contact said beveled ends 46 and 48 and be adjusted thereby to inactive position, Fig. 7, so that they may pass upwardly at opposite sides of the drill stem. When the sleeve 6 is lowered from the position shown by Fig. 7 to that disclosed by Fig. 8, diametrically opposed tongues 50 at its lower end enter 60 corresponding recesses 52 in the chuck 32 to

form a coupling which coacts with the feathers 8 in driving the sleeve 6 and the bits 14 when the drill stem 2 is rotated.

Ducts 33 extend from the tubular portion 35 of the drill stem 2 to the lower portion of 70 the chuck 32 for the purpose of discharging water forced downwardly through said drill stem to flush out the cuttings from the well.

The upper portion of the sleeve 6 is provided with a plurality of pivotally mounted 75 internal dogs 54 adapted to engage a peripheral shoulder 56 formed on the drill stem 2 by cutting therein a tapered annular recess 58.

The upper end of the sleeve 6 has a removable 80 cap 60 with an axial bore in which a tubular element 62 has a slidable fit. The lower end of the tubular element 62 is provided with an annular clamp 64 adapted to engage over the upper ends of the dogs 54, 85 Fig. 2, to hold them in engagement with the shoulder 56 and thereby prevent the sleeve 6 from moving upwardly on the drill stem 2 when the apparatus is in the drilling position disclosed by Fig. 4.

The upper portion of the tubular element 62 is provided with spaced collars 66 and 68 for engagement by dogs 70 forming part 90 of the elevator mechanism 73. The dogs 70 are pivotally mounted on a ring 72 slidably mounted within a tubular jacket 74. Independent downward movement of the ring 72 is limited by a pin 76, which projects inwardly from the jacket 74 into a peripheral 95 groove 78 in said ring.

The upper portion 80 of the ring 72 is reduced to slidably fit within the lower portion of a nut 82, the sliding movement being restricted by a pin 84 projecting from the ring 72 into a slot 86 within said nut 105 82. The nut 82 has a sliding fit in the jacket 74 and is provided at its lower margin with recesses 88 to receive the upper ends of the dogs 70 when in the position disclosed by Figs. 1 and 5. The nut 82 has threaded 110 therein an internal nut 90, which when adjusted upwardly permits the upper ends of the dogs 70 to pass inside of said nut 82 and be locked thereby in inactive position as disclosed by Fig. 6.

The nut 82 is slidably mounted upon the intermediate portion of a plunger 92, but caused to rotate therewith through the intermediary of groove and feather connections 94. The plunger 92 has a slidable fit 115 upon the drill stem 2 and within the ring 72, and is provided at a point above the nut 82 with a collar 96 which limits the slidable movement of the plunger 92 by contacting the top of the nut 82 or the bottom of a cap 120 98 threaded into the upper end of the jacket 74 and having an axial bore through which the plunger 92 slidably extends. The upper end of the plunger 92 is provided with suitable means such as eyes 100 to which the 125 130

lower ends of a cable 103 are attached for the purpose of raising and lowering the elevator mechanism 73, together with the sleeve 6 whenever the same is coupled to said elevator mechanism. The cable 103 may run over a sheave (not shown) at the surface.

In practice when starting to drill a well the drill stem 2 is equipped with the sleeve 6 and the bits 14, the elevator mechanism being omitted. As the work progresses and the bits 14 become dull and require sharpening, they, with the sleeve 6, are lifted to the surface by the elevator mechanism 73 which is lowered on the drill stem 2 for that purpose. Before lowering the elevator mechanism the nut 82 is adjusted upwardly so that the upper ends of the recesses 88 will just clear the upper ends of the dogs 70, Figs. 1 and 5, leaving the same to move freely on their pivots 71. The internal nut 90 is then adjusted to its lowermost position against the top of the ring 72 by rotating the plunger 92, to prevent the nut 82 from dropping behind the upper ends of the dogs 70 and locking them in inactive position as shown by Fig. 6. After the foregoing adjustments have been made the elevator mechanism 73 is lowered by the cable 103 until the jacket 74 rests upon the cap 60, which is a signal to the workmen that the elevator mechanism is ready to be lifted to the surface. As the elevator mechanism 73 is lifted with the dogs 70 resting on the beveled flange 75 at the lower end of the jacket 74, said flange forces the lower ends of said dogs 70 into engagement with the under side of the collar 66, Fig. 2, of the tubular element 62, which, on being lifted by the dogs 70, lifts the sleeve 6 through the intermediary of the clamp 64 which is lifted into engagement with the underside of the cap 60, Fig. 3. The upward movement of the clamp 64 frees the dogs 54 so that they can slide out of engagement with the beveled shoulder 56 to the position shown by Fig. 1, as the sleeve 6 moves upwardly with the elevator mechanism 73. As the sleeve 6 moves upwardly the bits 14 are turned approximately a quarter of a revolution from the position shown by Figs. 8 and 20, to the position disclosed by Figs. 7 and 19, by the upper ends of said bits contacting the beveled ends 46 and 48 of the recesses 42 and 44, respectively. When turned as stated, the bits 14 are free to move upwardly without impinging against the drill stem 2. On reaching the surface the bits 14 are removed from the sleeve 6 and resharpened or replaced by others.

Preparatory to again lowering the sleeve 6 and the bits 14 into the well, the tubular element 62 is pulled upwardly out of said sleeve until the bottom of the collar 68 passes above the hook ends 77 of the dogs 70, which are forced upwardly and backwardly out of

the way to the position disclosed by Fig. 6 by the beveled upper ends of the collars 66 and 68 contacting the beveled portions 70^a at the lower ends of said dogs 70. After the collar 68 passes above the hook ends 77 of the dogs 70 the latter move downwardly by the force of gravity and the beveled flange 75 forces said hook ends 77 against the tubular element 62 at a point beneath the collar 68, as shown by Fig. 1, the jacket 74 being supported by its cap 98 resting upon the collar 96 of the plunger 92 as shown by Figs. 1 and 5. The internal nut 90 is then screwed upwardly above the upper ends of the dogs 70 and the ring 72 until it contacts with the internal flange 83 at the upper end of the nut 82, by rotating the jacket 74 while the plunger 92 is held stationary. The cable 103 is then lowered with the elevator mechanism 73, the sleeve 6 and the bits 14, while the drill stem 2 is suspended with its chuck 32 high enough from the bottom of the well to permit the bits 14 to clear said bottom while being turned by the guides 36 from the inactive position disclosed by Fig. 7, to the active position disclosed by Fig. 8. The sleeve 6 is guided by the feathers 8 and grooves 10 into position upon the chuck 32 and in turn directs the bits 14 into proper relation with the guides 36. The drill stem 2 with the sleeve 6 and the elevator mechanism 73, are then simultaneously lowered until the bits 14 rest upon and are supported by the bottom of the well. The tubular element 62 and the elevator mechanism 73 continue their downward movement, permitting the beveled lower ends of the dogs 70 to engage the beveled upper reduced terminal 61 of the cap 60 which throws said dogs 70 out of engagement with the collar 68, as shown by Fig. 6. Just as the dogs 70 are disengaged from the collar 68 the jacket 74, which has an opening 79 at its lower end to receive the terminal 61, comes to rest upon the cap 60, while the plunger 92 continues its downward movement and pushes the tubular element 62 downwardly until its annular clamp 64 engages over the dogs 54 and holds them in locked engagement with the shoulder 56. As the plunger 92 forces the tubular element 62 downwardly the diametrically reduced portion 97 of the collar 96 impinges against the upper end of the internal nut 90, forcing the same downwardly so that it in turn will carry the nut 82 downwardly behind the upper ends of the dogs 70 and thus lock said dogs in the inactive position disclosed by Fig. 6. The elevator mechanism 73 is now ready to be lifted to the surface without the sleeve 6 as the dogs 70 are held in position by the nut 82 to clear the collars 66 and 68.

From the foregoing description, taken in connection with the drawings, it is apparent that I have provided an apparatus embody-

ing the advantages above pointed out, and while I have shown the preferred construction, combination and arrangement of parts, I reserve the right to all such modifications thereof as properly fall within the spirit and scope of the invention as claimed.

Having thus described my invention, what I claim and desire to secure by Letters Patent, is:

10. 1. In an apparatus of the character described, a rotary drill stem, a sleeve removably mounted on said drill stem, a pair of bits associated with said sleeve and arranged to turn part of a revolution to inactive position to clear the drill stem, means on the drill stem for turning said bits to inactive position, and means on the drill stem for securing the bits in active position.
20. 2. In an apparatus of the character described, a drill stem, a sleeve capable of being raised and lowered on said drill stem while the same is in lowered position in a well, a drilling tool carried by said sleeve, pivoted means for securing said sleeve from moving upwardly on the drill stem, and clamp means slidably mounted in the sleeve for holding said pivoted means in active position.
30. 3. In an apparatus of the character described, a drill stem, a sleeve removably mounted on said drill stem, a drilling tool carried by said sleeve, dogs for securing said sleeve against upward movement on the drill stem, clamp means operably mounted in the upper portion of the sleeve for holding said dogs in active position, and means controlled from the top of the well for disengaging said clamp means from the dogs.
40. 4. In an apparatus of the character described, a drill stem provided with a shoulder, a sleeve mounted for vertical movement on said drill stem, a drilling tool carried by said sleeve, dogs carried by the sleeve to releasably engage the shoulder on the drill stem so that said sleeve can be lifted independently of said drill stem, and means for locking the dogs in engagement with said shoulder and thereby securing the sleeve upon the drill stem.
50. 5. In an apparatus of the character described, a drill stem provided with a shoulder, a sleeve mounted for vertical movement on said drill stem, a drilling tool carried by said sleeve, dogs carried by the sleeve to releasably engage the shoulder on the drill stem so that said sleeve can be lifted independently of said drill stem, and an annular clamp for positively locking the dogs in engagement with said shoulder and thereby securing the sleeve to the drill stem.
60. 6. In an apparatus of the character described, a drill stem provided with a shoulder, a sleeve mounted for vertical movement on said drill stem, a drilling tool carried by said sleeve, dogs carried by the sleeve to

releasably engage the shoulder on the drill stem so that said sleeve can be lifted independently of said drill stem, means for positively locking the dogs in engagement with said shoulder and thereby securing the sleeve to the drill stem, and elevator mechanism for releasing said lock means from the dogs.

7. In an apparatus of the character described, a drill stem, a sleeve removably mounted on said drill stem, a drilling tool carried by said sleeve, a dog for securing said drill stem and sleeve together, an element associated with said sleeve to hold said dog in active position, and elevator mechanism for disengaging said element from the dog and raising and lowering the sleeve independently of the drill stem.

8. In an apparatus of the character described, a drill stem, a member arranged for independent vertical movement upon said drill stem, a drilling tool carried by said member, means for locking said member upon the drill stem, a dog for unlocking said locking means and raising and lowering said member, means for adjusting said dog to active position so that it may raise or lower said member, means for adjusting the dog to release position so that it may be lifted without said member, and means for holding said dog in released position.

9. In an apparatus of the character described, a drill stem, a member arranged to slip on and off of said drill stem, a drilling tool carried by said member, a dog for raising and lowering said member, a flange for adjusting said dog to active position, and means on the member carrying the drilling tool for adjusting the dog to release position.

10. In an apparatus of the character described, a drill stem, a member arranged for vertical movement upon said drill stem, a drilling tool carried by said member, means for locking said member upon the drill stem, a dog for releasing said locking means and raising and lowering said member, a ring extending around the drill stem and carrying said dog, a jacket for adjusting said dog to active position and in which said ring is mounted, and means for raising and lowering said jacket.

11. In an apparatus of the character described, a drill stem, a member arranged for vertical movement upon said drill stem, a bit carried by said member, means for locking said member upon the drill stem, a dog for releasing said locking means and raising and lowering said member, a jacket for adjusting said dog to active position, and means carried by said jacket for holding said dog in released position to permit the jacket to be lifted independently of said member.

12. In an apparatus of the character described, a drill stem, a member arranged to slip on and off of said drill stem, bits car-

ried by said member, a dog for raising and lowering said member, a jacket for adjusting said dog to active position, a cable for raising and lowering said jacket, means carried by said jacket for holding said dog in released position to permit the jacket to be lifted independently of said member, and a plunger slidably mounted on the drill stem for causing the last-mentioned means to actively engage said dog.

13. In an apparatus of the character described, a sleeve, bits turnably mounted at the lower portion of said sleeve, a drill stem on which said sleeve is slidably mounted, said drill stem having oppositely disposed recesses with beveled upper ends whereby the bits are turned to clear the drill stem when the sleeve is raised, and means at the lower portion of the drill stem for turning and locking the bits in drilling position when the sleeve is lowered.

14. In an apparatus of the character described, a drill stem, a sleeve slidably mounted upon said drill stem, a pair of flat rectangular bits turnably mounted at the lower portion of said sleeve and provided with longitudinal ribs, and interlocking means on the lower portion of the drill stem for locking the bits in drilling position and provided with grooves for receiving said ribs.

15. In an apparatus of the character described, a drill stem, a sleeve slidably mounted on said drill stem, a drilling tool carried by said sleeve, a dog for preventing said sleeve from sliding upon said drill stem, a tubular element slidably mounted in and projecting from the upper end of the sleeve and adapted to hold said dog in active position, and means for disengaging said tubular element from the dog and lifting said element and the sleeve on the drill stem.

16. In an apparatus of the character described, a drill stem, a sleeve slidably mounted on said drill stem, a drilling tool carried by said sleeve, a cap at the upper end of said sleeve, a dog for securing the sleeve to the drill stem, a tubular slidale element projecting through said cap and provided with clamp means for holding said dog in active position, and mechanism including a dog for engaging said tubular element and through the intermediacy thereof raise and lower the sleeve, the dog on said mechanism being disengaged by said cap from the tu-

bular element after the sleeve has been lowered.

17. In an apparatus of the character described, a drill stem, a sleeve slidably mounted on said drill stem, a drilling tool carried by said sleeve, a dog for engaging the drill stem and preventing said sleeve from sliding upwardly on said drill stem, a tubular element slidably mounted in and projecting from the upper end of the sleeve and adapted to hold said dog in active position, elevator mechanism consisting of means for engaging said tubular element and through the intermediacy thereof raising and lowering the sleeve, and a jacket having a flange for forcing said means into engagement with the tubular element.

18. In an apparatus of the character described, a drill stem, a member arranged for independent vertical movement upon said drill stem, a drilling tool carried by said member, means for securing said member upon the drill stem, dogs for unlocking said securing means and raising and lowering said member independently of the drill stem, means for adjusting said dogs to active position preparatory to lifting said member, and means on the member for adjusting said dogs to release position so that the same can be lifted independently of said member.

19. In an apparatus of the character described, a drill stem provided with a shoulder, a sleeve mounted for vertical movement on said drill stem, a drilling tool carried by said sleeve, dogs carried by the sleeve to releasably engage the shoulder on the drill stem so that said sleeve can be lifted independently of said drill stem, a tubular element vertically slidale in the upper portion of the sleeve and adapted to lock said dogs in engagement with the shoulder on the drill stem, two superimposed collars spaced apart upon said tubular element, elevator mechanism adapted to engage the lower collar and lower the drilling mechanism into a well and engage the upper collar and raise the drilling mechanism from the well, and means on the upper end of the sleeve for disengaging the elevator mechanism from said lower collar after the drilling mechanism has reached the bottom of the well.

In testimony whereof I affix my signature.
CHARLES W. HERRIN.
